UNITED STATES PATENT OFFICE.

HADLEY P. FAIRFIELD, OF WEST MEDFORD, ASSIGNOR TO GORDON MCKAY, OF CAMBRIDGE, MASSACHUSETTS, AND HENRY G. THOMPSON, OF MILFORD, CONNECTICUT, TRUSTEES.

LASTING-MACHINE.

SPECIFICATION forming part of Letters Patent No. 284,912, dated November 30, 1880.

Application filed October 1, 1880. (No model.)

To all whom it may concern:

Be it known that I, HADLEY P. FAIRFIELD, a citizen of the United States, residing at West Medford, in the county of Middlesex and State of Massachusetts, have invented 5 certain new and useful Improvements in Lasting-Machines; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 This invention relates to lasting-machines for boots and shoes, and is an improvement on United States Letters Patent No. 231,076, August 10, 1880, to which reference may be had.

20 In ordinary lasting-machines it is customary to employ at the heel of the last a U-shaped quarter-clamp to extend about the quarter on the last and hold it in position while the edges of the upper are turned over by the heel-crimping jaws or devices; but in said machines the 25

U-shaped clamps have never been so constructed and operated as to cause the clamps to impinge the quarter at the ends of the usual quarter or counter stiffener upon the 30 last near the shank of the shoe. In the operation of lasting a shoe it is quite essential to the performance of good work that the quarter at that part where the ends of the usual stiffening for the quarter ends should be forced closely and positively inward near, but just at the rear of, the shank of the shoe, and be there held while the edges of the shoe being lasted are tacked or secured to the inner sole. To 35 accomplish this I have combined with the

40 quarter-clamp suitable devices, preferably arms or levers, which at the proper time are automatically moved and caused to act upon the quarter-clamp near its ends, thus closing the open mouth or end of the said clamp, forcing its ends together against the quarter, causing the ends of the clamp terminating at the 45 ends of the quarter or counter stiffening just at the rear of the shank to thus positively force the quarter and counter stiffening against

the last quite up to or into the shank, thus 50 fitting and shaping the quarter and counter to the contour of the heel of the last, and holding it there while the edges of the shoe upper and quarter are turned over upon the inner sole, thus preventing bulging at the 55 shank. These arms or levers, acting upon the quarter-clamp, also determine and maintain the last in central position in the machine.

In heavy brogan-work, where the counter-stiffening is very thick, I find it of great advantage in mechanical lasting to divide or slot the ends of the clamp so as not to bear upon the side of the quarter just at that point or along the line where the upper curved edge of the quarter-stiffening and quarter contact, to 65 thus permit the ends of the clamp to bear upon the quarter near the inner sole, and also at a point beyond the upper edge of the stiffening, thus holding the quarter and last firmly and avoiding the rocking of the last, as would 70 be the case were the jaws not slotted or cut away, or shaped at their ends so as not to rest upon the quarter immediately outside the upper edge of the quarter-stiffening.

Figure 1 is a partial vertical cross-section 75 of sufficient of a lasting-machine to illustrate my invention, the parts being considered fully closed together, as at the inward position of the usual jaws. Fig. 2 represents the same in side elevation, a portion of one of the usual jaw-carriers and pad-actuating levers at the right of Fig. 1 being broken off at the top to better show the pads and the levers or arms for moving the toe-pads and quarter-clamps together; Fig. 3, a top view of Fig. 1; and Fig. 80 4, a detail, illustrating the inner member of the quarter-clamp in position on the quarter of a shoe, the broken line showing the usual stiffening for the quarter.

In the drawings, the carriers M, levers b, 90 wedges L, K, their carrying-rod J, the toe pads or clamps l, arms e, shank-pads c, levers r, and screw m are all substantially as in the United States Patent referred to, and need not therefore be herein particularly described. The 95 said patent did not show a quarter-clamp. The quarter-clamp herein shown is composed of an outer U-shaped shell of metal, a sheet,

f, of india-rubber or other elastic material, and an inner shell, *g*, also of sheet metal. As so far described this quarter-clamp is common and in use. I slot this inner shell, as at 4, or 5 otherwise shape or form it that only the portions 2 3 at the lower and upper portions of the shell touch the quarter, the shell being so shaped at its ends as not to bear upon the side of the quarter in the line where the quarter 10 and upper edge of the usual quarter-stiffening come together. This construction of the inner shell enables the quarter, both above and below the upper edge of the thick stiffening, to be held firmly in place in contact with the last. 15 At the sides of the quarter-clamps I have placed devices, shown as levers *h*, pivoted at *h*. These levers are provided each with adjusting-screws *h*², which, as the levers *b* are closed by the wedge *L*, act upon the said screws, and, 20 according to their position, cause the levers *h*, in contact with the outer shell of the quarter-clamp, to push upon and simultaneously close the ends of the said clamp together, thus forcing the quarter and stiffener connected with 25 it firmly against the last quite up to and into the shank of the last, holding the same powerfully during the lasting operation. The toe-pads *l* are simultaneously closed upon the upper at the toe of the last by the levers *r*. The 30 shank-pads *c* are fixed with relation to the length of the last; but the levers *r* and *h*, that actuate the toe-pads and quarter-clamps, are fixed upon carriages *S S'*, connected and made simultaneously adjustable by means of the 35 screw *n*, thus enabling the said levers to act for shoes and lasts of different sizes, and for rights and lefts, as is particularly described with relation to the toe and shank pads of the patent hereinbefore referred to. The rod 40 *J* (also shown in the said patent) is herein re-

ciprocated at the proper times through the agency of a toggle-joint, *m m*², connected with a link, *m*³. This link has upon it an adjustable hook, *m*⁴, which is acted upon by a pin, *s*, of an arm, *m*⁵, of the main shaft *p* when it is desired to straighten the toggle and lift the rod. The shaft *p* has upon it a toothed gear, *A*, driven by gear *B* on shaft *C*, having a belt-driven pulley, *D*. 45

In Fig. 4 the broken line indicates the upper 50 edge of the quarter-stiffener, and it may be either at the inner or outer side of the quarter, according to the class of shoe being lasted.

I claim—

1. In a lasting-machine, the quarter-clamp, 55 combined with means, substantially as described, to close and hold its ends together upon the quarter and counter during the lasting operation, substantially as set forth.

2. The quarter-clamp and levers or arms to 60 positively close its ends upon the quarter, and the toe-pads and levers to close them upon the toe and heel of the shoe, combined with a screw to simultaneously adjust the said pads to adapt them to lasts and shoes of different 65 sizes, substantially as set forth.

3. In a lasting-machine, the quarter-clamp having its inner ends at 2 3 shaped to bear upon the quarter above and below the junction of the upper edge of the quarter-stiffening and 70 quarter at the sides of the quarter to hold the quarter firmly against the last, substantially as and for the purpose set forth.

In testimony whereof I affix my signature in presence of two witnesses.

HADLEY P. FAIRFIELD.
